Inventor:

John Kirby Jr.

UNITED STATES PATENT OFFICE.

JOHN KIRBY, JR., OF DAYTON, OHIO, ASSIGNOR TO THE DAYTON MANUFACTURING COMPANY, OF SAME PLACE.

LAMP.

SPECIFICATION forming part of Letters Patent No. 537,209, dated April 9, 1895.

Application filed October 16, 1893. Serial No. 488,265. (No model.)

To all whom it may concern:

Be it known that I, JOHN KIRBY, Jr., a citizen of the United States, residing at Dayton, in the county of Montgomery and State of Ohio, have invented certain new and useful Improvements in Lamps, of which the following is a specification, reference being had therein to the accompanying drawing.

My invention relates to a reflector embodying means for the attachment thereto of a series of incandescent electric lamps; and it also relates to the construction of said reflector in such manner as to adapt it to be combined with an ordinary oil or candle lamp, whereby either system of lighting may be used at will.

The invention consists in a reflector having a convex reflecting-surface, an annular recess in said surface, and a ring fitted in said recess and provided with a series of nipples adapted to engage with the sockets of a series of incandescent electric lamps.

The accompanying drawing forming part of this specification is a perspective view of a reflector constructed in accordance with my invention combined with an ordinary street-car lamp arranged for burning candles, a portion of the view being broken away to show the manner in which the electric lamps are attached, and also to illustrate the construction and operation of the globe-holder.

In the drawing, A represents the body-ring, and B the hangers of the lamp.

C is a candle-holder of an ordinary type, which may, if desired be substituted by an oil-holder.

D is the globe, supported at its bottom by the body-ring.

E is the reflector, the outer or reflecting surface of which is convex in form, as shown in the drawing. In this convex reflecting surface is formed an annular recess, in which is fitted a metal ring H, provided with a number of radial bosses b and screw-threaded nipples c, to receive the sockets of a series of incandescent electric lamps J, the latter being provided with shades K. Said nipples and bosses have axial openings, which register with holes formed through the reflector for the passage of wires d e for carrying the elec-

tric current to the lamps J, whereby said wires are completely housed and hidden from view. The ring H is polished, and when in place on the reflector it will also present a reflecting surface without casting a shadow. 55 Furthermore, as the metal from which reflectors of this class are made is usually quite thin, lamps attached directly to the reflector would not have adequate support; and this same objection would apply to the ring if it were 60 dependent on rivets as its support on the reflector. However, by countersinking the reflector to receive the ring these difficulties are avoided, as the ring acts to reinforce the reflector and spreads the weight of the lamps 65 over a comparatively large area, the ring and reflector forming, of course, a continuous reflecting surface.

In the central portion of the reflector is formed an interiorly screw-threaded sleeve 70 F, with which engages an exteriorly screw-threaded globe-holder G, adjustable vertically therein, as seen in dotted lines in the drawing, and adapted to engage with and steady the upper portion of the globe D of an 75 ordinary oil or candle lamp. By this construction the holder is carried by the reflector, and is therefore always at hand and readily and easily adjusted to hold the globe.

The reflector is preferably secured to the 80 upper ends of the hangers, as shown, thus making a complete fixture which can be handled and placed in position in a car as a single piece. It may, however, be separate from the hangers, which, with the body-ring constitute the frame of the lamp; but the arrangement shown and above described affords 85 greater convenience to persons handling and placing the lamp in position for use.

The lamp may be secured to the car-ceiling 90 by screws passing through the upper ends of the hangers in the usual manner; and I prefer that the screws also pass through the reflector, as shown.

Having thus described my invention, what 95 I claim as new, and desire to secure by Letters Patent, is—

1. A reflector having a convex reflecting-surface, an annular recess in said surface, and a ring fitted in said recess and provided with 100

a series of nipples adapted to engage with the sockets of a series of incandescent electric lamps.

2. A reflector having a convex reflecting-surface, an annular recess in said surface, a ring fitted in said recess, and a series of screw-threaded nipples carried by said ring and adapted to engage with the sockets of a series

of electric lamps, said nipples having axial openings in register with holes formed in the reflector for the passage therethrough of the wires to the electric lamps.

JOHN KIRBY, JR.
